The ornamental design for a cigarette machine holder, as shown and described.

DESCRIPTION

FIG. 1 is a front perspective view of a first embodiment of a cigarette machine holder with a cigarette machine shown in broken lines positioned within the holder;

FIG. 2 is a front perspective view corresponding to FIG. 1, with the cigarette machine removed;

FIG. 3 is a front elevation view of the cigarette machine holder of FIGS. 1 and 2;

FIG. 4 is a rear elevation view of the cigarette machine holder of FIGS. 1 and 2;

FIG. 5 is a left side elevation view of the cigarette machine holder of FIGS. 1 and 2, the right side elevation view being identical;

FIG. 6 is a top plan view of the cigarette machine holder of FIGS. 1 and 2; and,

FIG. 7 is a bottom plan view of the cigarette machine holder of FIGS. 1 and 2.

The broken lines in FIGS. 1-6 illustrate portions of the cigarette machine holder and form no part of the claimed design.
